UNITED STATES PATENT OFFICE

GUSTAV SÜLLWALD, OF FREIBURG, GERMANY

PACKING CIGARETTES AND THE LIKE

Application filed March 15, 1929, Serial No. 347,428, and in Germany August 20, 1925.

This invention has reference to the packing of cigarettes and the like in which said articles are disposed in encasing sleeves or the like flexibly or similarly connected to each other in substantially parallel and preferably spaced relationship, so that the articles with their carriers may be rolled up into a coil or spiral-like aggregate from which the individual aggregates may be readily separated. In accordance with this invention a protective casing is provided in which the cigarette or similar article is securely retained against injury from vibration or too dense packing and without being secured in position by clamping or similar means as provided in the roller casings heretofore suggested. Broadly considered, the device according to this invention comprises a combination of two or more flexible strips, bands, sheets or the like connected to each other at suitable distances corresponding to the convenient seating of the cigarettes or the like and of such width that the outer edges of the strips, sheets or the like project beyond the ends of the articles, so as to allow of the connecting of the edges to each other at a sufficient distance from the ends of the articles to insure of their being retained absolutely proof against the access of dust, air and moisture and of other deteriorating agents.

The invention is shown on the accompanying drawings in several embodiments by way of exemplification in Figs. 1 and 2 in longitudinal sections showing two modifications of the packing. Fig. 3 is a longitudinal section of another modification on an enlarged scale. Fig. 4 is a plan view of the general arrangement of the packing means according to this invention; and Fig. 5 is a cross-section of Fig. 4.

The cigarettes *c* which are arranged parallel or substantially parallel to each other are covered on both sides by continuous strips *a* and *b* of any suitable length. The strips are connected to each other intermediate the cigarettes or the like by pasting, gumming, stitching or by equivalent means, as indicated at *d* in the drawings. In order to provide for the easy separation of any amount

of the encased cigarettes or the like from the strip, the strips or sheets *a* and *b* are preferably weakened at the points of connection *d* in any well-known manner as by perforation, scoring or the like, the perforation being for instance indicated at *i* in the drawings. The width of the strips *a* and *b* exceeds the length of the cigarette *c* at both ends thereof, so that the marginal parts of the strips *a* and *b* project beyond the cigarettes on both sides, as appears from Figs. 4 and 5 of the drawings. By this means each individual cigarette or the like is securely enclosed and protected from injury. The projecting edges *e* of the protecting strip may be connected to each other by gumming, pasting, stitching or by similar means. The strips *b*, *a* may comprise one or several layers. Thus, in the modification according to Fig. 3 I have provided two layers *b* on the bottom side of the sleeve-carrying strips.

In accordance with the modification shown in Fig. 5 the covering strips or sheets may comprise one single continuous sheet, that is to say, they will be integral with each other and folded up at one side of the article, as particularly shown at the upper part of Fig. 5 of the drawings. This kind of sheet comprising the two halves *a* and *b* is folded over the cigarettes transversely thereof, after they have been placed in position, and the open ends of the two legs or halves are pasted up and connected at their lower edge *e*. With a view of providing for a very tight closure of the ends of the cigarettes and for the purpose of securing them in position and protecting them from injury by vibration and of preventing dropping out of the tobacco, an intermediate layer *g* of any suitable soft and well-closing material is inserted between the ends of the individual cigarette and the closed ends of the sleeve-like casing. This protecting layer *g* may for instance consist of a wad of cotton or of very thin, paper-like pulp, vegetable fibres, kapok, or the like.

In the preferred construction according to Fig. 5 the ends of the casing are flattened, by which means a certain tensioning is produced in the longitudinal direction of the

casing without thereby affecting the walls or the contents of the cigarette itself. The protective layer is thereby likewise secured in position, so as to prevent the possibility of 6 shaking and the thereby ensuing injuring of the cigarettes and the tamping of the open ends of the cigarette, which is likely to occur in case the cigarette is loosely contained in the sleeve-like or cylindrical casing.

10 In order to facilitate the opening of each individual enclosing sleeve after the separation from the rest of the packing tearing means may be provided, so as to allow of opening each particular sleeve very rapidly 15 and without likelihood of injuriously affecting the cigarettes or the filling thereof. For this purpose a tearing thread, wire or the like *f* may be inserted in the space between the sleeve and the cigarette, so as to project 20 on one or both sides of the packing, as indicated in Figs. 3 and 4 of the drawings. This thread or the like *f* may be secured, if desired, to the sleeve or to the base *b* out of contact with the cigarette.

25 The finished packet of the seating means according to this invention with the articles contained therein may be given any suitable or desired shape by rolling or packing. It is, of course, also possible to arrange the cigarettes with their carriers in a flat condition 30 in boxes, cases or the like. Any desired number of cigarettes may be severed off from the packet and without any liability of air or moisture coming in contact with even a single 35 cigarette, and by this means the possibility of drying up of the tobacco and of the liberation and escape of the aromatic oils of the cigarette is prevented. The very simple construction of the carrying or packing means 40 according to this invention is a point of great importance particularly for the cheaper grades of cigarettes, the costs of which will thereby not be materially increased, while the quality of the goods is improved.

45 It should be pointed out that instead of one or two strips enclosing means may be provided comprising three or more strips as indicated for instance in Fig. 3 of the drawings. In this case one of the outer strips may 50 act as a protecting and supporting base for the several units.

The strips or sheets constituting the enclosing means for the cigarettes according to this invention may be made of thin paper or 55 of paper-like, transparent cellulose or the like, or it may consist of metal foil, such as for instance of aluminium foil or the like. By the employment of transparent material there is the advantage that the packed goods 60 are visible to the buyer. It is an important advantage in connection with my invention that there is a saving in packing material, inasmuch as the carrying means according to the invention are already providing a suffi- 65 ciently secure and protective packing. The

sleeves with their connecting and carrying means may be easily and rapidly manufactured by machinery and of comparatively cheap material. The employment of enclosing strips projecting beyond the ends of the 70 articles will admit of the absolutely dust-proof and air-tight enclosing of the cigarettes, after positioning them in the sleeves, and without the use of special closing and protecting means; it is merely necessary to unite the projecting marginal portions of the sleeves by pasting, gumming, stitching, folding or the like, and all these operations may be effected on the packing machine, while the strips themselves are united to each other 75 intermediate the cigarettes. In the packing means for individual articles, as suggested in the previous art, it is impossible to provide an absolutely dust-proof and air-tight closure of the individual cigarettes on all sides 80 thereof, and to protect them against injuries from shaking, vibration or from the action of the atmosphere. Moreover, the manufacture of individual packings and the connection thereof by special connecting means is far 85 more expensive than the method and device in accordance with this invention.

90 While I have described my invention in connection with what I consider the best embodiments thereof, it will have to be understood that deviations may occur and modifications may be made to more advantageously adapt the invention to its purpose and to local conditions, such changes and modifications falling within the purview of my 95 invention, except as otherwise appears from the claims hereunto annexed.

100 I claim:

1. In a device of the kind described, a plurality of spacedly parallel, substantially 105 channel-shaped, longitudinally extending cellules, a separable connecting web between each of the cellules, ridge-like outwardly projecting separable closures at the opposite ends of the cellules, endwise projecting 110 strings within the cellules, adjacent the webs, and substantially parallel therewith, and plugs of resilient material within the cellules at the closed ends thereof.

2. In a device of the kind described, a plurality of parallel, substantially sleeve-like, longitudinally extending carriers for cigarettes and the like, flexible, separable connecting means between said carriers, and outwardly projecting substantially flattened 115 and substantially diametrically disposed ridge-like closing and opening means integral with the carriers at opposite ends thereof.

3. In a device of the kind described, an upper continuous web of flexible sheet-like 125 material of substantially unchanging thickness, and a lower continuous web of flexible sheet-like material of substantially unchanging thickness, both webs being superimposed longitudinally of each other and edgewise 130

5 united, comprising a plurality of corrugated, spacedy parallel, sleeve-like portions of substantially unchanging diameter, running transversely of said webs, and flattened pasted-together connecting strips of said webs intermediate the corrugated portions and closures at the ends of the sleeve-like portions.

10 4. In a device of the kind described, two superimposed continuous and edgewise united layers of equal size of a longitudinally doubled-up sheet of flexible material, comprising a plurality of spaced parallel, end-
15 wise closed, substantially sleeve-like corrugated portions of unchanging diameter transversely of the sheet, and separable strips of superimposingly united portions of said layers intermediate the sleeve-like portions thereof.
